UNITED STATES PATENT OFFICE.

CYRUS HANKINS, OF BALTIMORE, MARYLAND, ASSIGNOR TO THE SYMINGTON COMPANY, OF NEW YORK, N. Y., A CORPORATION OF MARYLAND.

SIDE FRAME.

Application filed May 5, 1925. Serial No. 28,094.

This invention relates to side frames for railway car trucks, and more particularly to such side frames formed from integral blanks of sheet-metal folded upon themselves.

One of the principal objects of the invention, generally considered, is the formation of wrought metal side frames from blanks folded upon themselves and riveted along diagonal lines adjacent the lower portions thereof with drainage openings provided between said rivets for minimizing rusting and consequent deterioration of the frame.

An object of my invention is the provision of a pressed metal car truck side frame in which spaced side wall portions are provided adjacent their lower edges with downwardly disposed connecting flanged portions so shaped or corrugated that they are adapted 15 for connection by rivets or the like at their contacting portions, leaving spaced portions between said connected portions serving as drainage openings for the elimination of moisture and the prevention of rust and corrosion.

Another object of the invention is the provision of sheet-metal side frames formed with spaced wall portions, said wall portions being formed with a relatively central 20 window opening, the periphery of said window opening being framed by inwardly disposed flanges from said wall portions, wear plates connecting the inner and outer walls of said frame, extending over a portion of 25 said flanges, and united to said frame by rivets, some of which extend directly through the outer and inner side wall portions of the frame and corresponding flanged portions of the wear plate, and others of which extend through diagonally disposed flanged portions of the frame and correspondingly disposed portions of the wear plate.

Another object of my invention is the provision of a sheet-metal truck side frame formed with wear plates riveted thereto, and brake hanger brackets connected to the inner side wall of the frame adjacent said wear plates, common connecting means serving to connect portions of said wear plates and brake hanger brackets with said side frame.

Another object of my invention is the provision of wrought metal side frames for

railway cars with journal box pockets 55 formed in the ends thereof, and journal boxes with specially designed roof portions engaged in said pockets.

A further object of my invention is the provision of sheet-metal side frames formed 60 from blanks folded upon themselves and connected by diagonal lines of rivets along the lower portions thereof, the ends of said frames being formed with recesses for the reception of specially designed journal boxes, 65 said journal boxes being formed with lugs extending between flanged extensions from the side frame and riveted thereto.

Other objects and advantages of the invention, relating to the particular arrangement and construction of the various parts, 70 will become apparent as the description proceeds.

Referring to the drawings illustrating my invention, the scope whereof is defined by 75 the claims:

Figure 1 is a side elevation, partly in longitudinal section, showing the side frame embodying my invention and having connected thereto journal boxes, wear plates 80 and brake hanger brackets.

Figure 2 is a plan view, partly in horizontal section, on the line 2—2 of Figure 1, and partly broken away.

Figure 3 is a transverse sectional view on 85 the line 3—3 of Figure 1, looking in the direction of the arrows.

Figure 4 is a transverse sectional view on the line 4—4 of Figure 1, looking in the direction of the arrows.

Figure 5 is a transverse sectional view on 90 the line 5—5 of Figure 1, looking in the direction of the arrows.

Figure 6 is an end view of the frame and connected journal box, as shown in Figure 1.

Figure 7 is a horizontal sectional view on the line 7—7 of Figure 1.

Figure 8 is a transverse sectional view on 95 the line 8—8 of Figure 1.

Referring to the drawings, in which similar reference characters designate like parts in the several views, there is shown a side frame 1 formed from a single blank which is adapted for being cut from a substantially 100 square plate. This will be apparent from considering that the extreme length of the frame is substantially equal to twice the depth plus twice the width.

Each half of the frame 1 comprises a plurality of top arch bar portions 2, bottom arch bar portions 3, and truck column portions 4. The blank for the frame, after having been cut to form the parts enumerated and formed with flanges 5 framing the window opening 6, flanges 7 framing the triangular openings on opposite sides of the window opening 6, and flanges 8 along the lower edges of the lower arch bar portions 3, is then bent over on itself to form spaced side walls 9 and 10, as shown most clearly in Figure 2.

The flanges 8 in the center or extreme lower portions of the bottom arch bar portion 3 are simply inwardly extending flanges like the flanges 5 and 7. Those portions of the flanges 8, however, which are diagonally disposed on opposite sides of the central horizontal portion of the bottom arch bar portion 3, are specially corrugated or formed with downward extensions 11, formed with inwardly disposed bosses or abutment portions 12. Although four of such corrugated or abutment portions 12 are shown on each side of the window opening in the frame, I do not wish to be restricted to such a showing as any desired number may be employed.

As shown most clearly in Figure 3, the complementary halves or spaced side walls 9 and 10 of the frame are connected, besides the unitary connection where the blank is bent upon itself at the top of the frame, by rivets 13 through the abutting corrugated or embossed portions 12 on the downwardly extending portions 11 of the flanges 8.

On account of the embossed portions 12, as will be apparent from considering Figure 3 particularly, there are apertures 14 left between each pair of rivets. Such apertures serve for drainage purposes and minimize the entrapment of water or the like between the inner and outer side walls of the frame. It will be apparent that without such drainage openings any accumulation of moisture between the abutting portions of the side walls would have a rusting or deteriorating effect thereon and would not dry off as quickly as desired if any large area between plates was provided for such moisture to accumulate.

The extreme outer or upper ends of the flanges 8 are curved concavely downward, as shown at 15, for the reception of the journal boxes 16, the roof portions of which are correspondingly curved.

As shown most clearly in Figure 1, the roof portions 17 of said journal boxes are formed double, the upper wall 18 being curved to correspond with the curved portion 15 of the flanges 8, and the lower portion 19 being of the usual flat formation.

The portions 18 and 19 of the journal box

roof are preferably connected by a bracing web 20, preferably centrally disposed, as illustrated.

Each journal box 16 is preferably provided with a lug 21 extending between the portions 11 of the flanges 8 or a triangular extension 22 thereof. The lug 21 is preferably apertured at 23, said aperture being surrounded by a boss portion 24, the thickness of the lug over the boss portion 24 being substantially equal to the spacing between the downwardly extending portions 11 of the flanges 8.

Although a boss portion is shown on the journal box lug, the same effect might be accomplished by inwardly embossing the extension 22 adjacent the aperture 23 so that the distance between the embossed portions on 22 would approximate the thickness of the lug 21 without the provision of any boss thereon. The idea involved in this construction is the same as that involved in corrugating or embossing the diagonally disposed connecting portions 11 of the flanges 8, namely, the minimization of areas between overlapping portions of metal where moisture could accumulate with deleterious results.

Additional means for connecting the journal boxes 16 with the side frame may comprise upstanding flanges 25 and 26 on said journal boxes embracing the ends of the frame. The flanges 25 and 26 and the adjacent portions of the frame are preferably each formed with a corrugation 27, those corrugations in the frame gradually merging into the flat side wall portions thereof, as shown at 28.

The window opening 6, as shown particularly in Figure 1, is narrowed adjacent the upper half thereof, as is usual, and provided with wear plates 29 and 30, the lower portions of said wear plates preferably overlapping the junction formed in the flange 5 where the window opening 6 changes in width. The flanges 5 adjacent the widest part of the window opening 6 are plane and extend toward each other, that is, those from the outer side wall of the frame extend toward those from the inner side wall, and vice versa. The vertical flanges adjacent the narrow portion of the window opening, however, are of special construction, as illustrated most clearly in Figure 2. That is, they are formed with diagonal portions 31 connecting inwardly disposed parallel portions 32 with the corresponding side wall portions of the frame. From these parallel portions 32 extend transversely disposed flanged portions 33 which merge with the flanges 5 of the wider portions of the window opening.

The purpose of such construction is to provide bolster side wear portions which are disposed closer together than the inner

and outer side walls of the frame. That is, the parallel portions 32 are disposed a shorter distance with respect to each other than the inner and outer side walls 9 and 10 of said frame. Over these specially formed flanged portions 31—32—33 are secured the correspondingly formed wear plates 29 and 30, as illustrated, the securing means therefor preferably taking the form of upper rivets 34 extending through the diagonal portions 31 of the frame and corresponding diagonal portions 35 on the wear plates, and lower rivets 36, preferably extending through longitudinally extending flanged portions 37 of the wear plates 29 and 30 and the corresponding side walls of the frame, the lower connection being made preferably below the junction where the window opening changes in width.

On account of this construction all that is really normally necessary for connecting the wear plates to the frame, is one transversely disposed rivet 36 and one diagonally disposed rivet 34 through each flange of each wear plate. However, when the brake hanger brackets 38 are employed, it is preferable to extend the inner flange of each wear plate, as shown in dotted lines in Figure 1, and employ a common rivet 39 for connecting a portion of the base of the brake hanger bracket 38, the flange of the wear plate 29 or 30 and the side frame.

Using the common rivet 39 for connecting these members, the wear plate 29 or 30 being embraced between the other two parts, raises the corresponding base portion of the brake hanger bracket so that the additional securing means 40, preferably take the form of rivets extending through an offset base portion 41 of the brake hanger bracket 38 and the adjacent portion of the side wall of the frame.

Because of the described construction of wear plate 29 or 30 and the mode of connection between the same and the side frame, a transverse or central wearing surface 42 is provided on each wear plate, together with side wearing surfaces 43 on the flanged portions thereof, all of said surfaces being unobstructed by rivet heads or broken by perforations or indentures so that a maximum wearing area is provided within the limits allowed.

In view of the foregoing, it will be apparent that an integral pressed steel side frame has been provided which is conveniently formed by folding a properly shaped blank upon itself and diagonally riveting the same at isolated points to provide drainage openings between the rivets. The wear plates on this frame are connected by rivets through rivet holes positioned in different planes and at different elevations so that

maximum efficiency of riveting strength is secured as well as a freedom from rivet interference on the necessary wearing areas.

Brake hanger brackets are also connected to the frame and common riveting means serve for connecting portions thereof and the corresponding wear plates with the side frame.

The journal boxes employed with the frame have roofs of special shape so as to cooperate efficiently with the pockets provided at the ends of the frame, and journal box lugs are provided for convenient and efficient connection with the frame between downwardly extending flanged portions thereof.

Having now described my invention, what I claim is:

1. A car truck side frame comprising inner and outer walls arranged in spaced relation, each of said walls having a plurality of truck column portions, a plurality of top arch bar portions and a plurality of bottom arch bar portions, said bottom arch bar portions being provided with flanges, projecting inwardly of the side walls, having portions thereof extending downwardly therefrom, and means uniting the downwardly extending portions, leaving apertures between said uniting means.

2. A car truck side frame comprising inner and outer walls arranged in spaced relation, each of said walls having a plurality of truck column portions, a plurality of top arch bar portions, and a plurality of bottom arch bar portions, said bottom arch bar portions being provided with flanges, projecting inwardly of the side walls, having portions thereof extending downwardly therefrom, formed with engaging portions separated by spaced portions, and connecting means joining said downwardly extending portions at the engaging portion thereof.

3. A car truck side frame comprising inner and outer walls arranged in spaced relation each of said walls having a plurality of truck column portions, a plurality of top arch bar portions and a plurality of bottom arch bar portions, said bottom arch bar portions being provided with flanges, projecting inwardly of the side walls, having portions thereof extending downwardly therefrom and engaging at spaced portions only thereof, and rivets connecting said engaging portions only, leaving apertures therebetween.

4. A car truck side frame formed of a single blank folded on itself and riveted along diagonal lines at isolated points of engagement, leaving drainage openings therebetween.

5. A car truck side frame comprising a single sheet of metal folded on itself to form spaced side walls, portions of the lower

edges of said side walls being corrugated transversely of said edges and connected at meeting portions of the corrugations.

5 6. A car truck side frame comprising spaced side walls, diagonal portions of said walls being formed as bottom arch bar portions, the lower edges of said diagonal portions being formed with substantially parallel spaced depending flanges, and means 10 uniting said flanges at intervals.

15 7. A car truck side frame comprising spaced side walls, diagonal portions of said walls being formed as bottom arch bar portions, the lower edges of said diagonal portions being formed with substantially parallel spaced depending flanges, separated portions 20 on said flanges abutting, and rivet means connecting said abutting portions.

25 8. A car truck side frame comprising spaced side walls formed with arch bar and truck column portions, leaving a window opening therebetween, the edges of the arch bar portions adjacent the window opening being flanged inwardly, part of the flanged 30 portions being diagonally disposed and joining inwardly disposed substantially parallel portions with the main walls of the frame, correspondingly formed wear plates extending over and joining said flanged portions, and connecting means uniting said plates with the flanged portions and extending through the diagonally disposed portions thereof.

35 9. A car truck side frame comprising spaced side walls formed with arch bar and truck column portions, leaving a window opening therebetween, the edges of the arch bar portions adjacent the window opening being flanged inwardly, part of the flanged 40 portions being diagonally disposed and joining inwardly disposed substantially parallel portions with the main walls of the frame, correspondingly formed wear plates extending over and joining said flanged portions, and connecting means uniting said plates with the flanged portions and extending through the diagonally disposed portions thereof, and additional connecting means extending 45 through said wear plates and the said walls 50 of the frame.

55 10. A car truck side frame comprising spaced side walls formed with arch bar and truck column portions leaving a window opening therebetween, said window opening being formed narrower adjacent the top portion and the edges of said narrower portion being formed with flanges, portions of which are diagonally disposed and extending toward each other, and wear plates positioned 60 over said flanges and provided with correspondingly flanged portions overlapping the diagonally disposed portions of the side frame flanges and provided with extensions 65 overlapping the side walls of the frame, and rivets extending through the diagonal por-

tions and the side walls for connecting said wear plates to the side frame.

70 11. A car truck side frame comprising spaced side walls formed with arch bar and truck column portions leaving a window opening therebetween, the edges of the arch bar portions adjacent the window opening being flanged inwardly, portions of said flanges being diagonally disposed, and bolster wear plates formed with side wear portions, and diagonally disposed extensions therefrom overlying the flanges surrounding the window opening of the side frame and connected thereto by rivets extending through diagonally disposed portions thereof 80 beyond the side wear portions and corresponding diagonally disposed portions of the side frame flanges.

85 12. A car truck side frame comprising spaced side walls formed with arch bar and truck column portions providing a window opening therebetween, the edges of the arch bar portions adjacent the window opening being flanged inwardly, part of the flanged 90 portions being diagonally disposed and joining inwardly disposed portions substantially parallel with the main walls of the frame, correspondingly formed wear plates extending over and joining said flanged portions, and diagonally disposed rivets extending through the diagonal portions of the wear plates and side frame and transverse rivets through extensions from said diagonal portions of the wear plates and the side walls 95 of the frame, all of said rivets being beyond the junction of the diagonally disposed portions and the inwardly disposed portions of the wear plates.

100 13. A car truck side frame comprising spaced side walls formed with arch bar and truck column portions leaving a window opening therebetween, the edges of the arch bar portions adjacent the window opening being flanged inwardly, and correspondingly 105 formed bolster wear plates connected over said flanged portions of the frame, and brake hanger brackets connected to the inner wall of said side frame adjacent said wear plates, and common connecting means between said frame and the cooperating wear plates and 110 brackets.

115 14. A car truck side frame comprising spaced side walls formed with arch bar and truck column portions leaving a window opening therebetween, the periphery of said window opening being framed by inwardly extending flanges from the side wall portions, correspondingly formed wear plates embracing parts of the truck column portions, brake hanger brackets positioned adjacent said wear plates, and common connecting means extending through said frame, wear plates and brake hanger brackets, said 120 brake hanger brackets being provided with 125 offset portions beyond the wear plates con- 130

nected independently with respect to the side frame.

15. A car truck side frame comprising spaced walls each of which has a plurality of bottom arch bar portions, inwardly extending flanges thereon, the upper portions of which are curved to provide journal box recesses, and a journal box at each end of said frame with a correspondingly curved upper wall engaging said curved flanges and seated within one of said recesses.

16. A car truck side frame comprising spaced side walls, each of which is formed with a plurality of top arch bar portions, bottom arch bar portions and truck column portions, inwardly extending flanges on the lower edges of the lower arch bar portions, the outer end portions of said flanges being curved concavely downward to provide journal box recesses, a journal box at each end of said frame suitably connected thereto, each journal box being provided with a double upper wall, the upper part of said double wall being curved and braced to the lower wall by a central connecting rib, the upper portion of the double wall being correspondingly curved and seated in one of the journal box recesses of the frame.

17. A car truck side frame comprising inner and outer walls arranged in spaced relation, each of said walls having a plurality of truck column portions, a plurality of top arch bar portions, and a plurality of bottom arch bar portions, said bottom arch bar portions provided with flanges projecting inwardly of the side walls having portions thereof extending downwardly therefrom, means uniting said downwardly extending portions, a journal box mounted at each end of said frame and provided

with a lug extending between said downwardly extending portions, some of said uniting means extending through the journal box lugs and leaving apertures between all of said uniting means.

18. A car truck side frame comprising inner and outer walls arranged in spaced relation, said walls each being provided with a plurality of truck column portions, top arch bar portions and bottom arch bar portions, said bottom arch bar portions being formed with flanges projecting inwardly of the side walls and having portions extending downwardly therefrom, a journal box connected to said side frame at each end thereof and provided with a lug formed with a bossed aperture, said lug extending between said downwardly extending flanged portions, and rivet means uniting said flanged portions and lug near the outer ends thereof, the remaining parts of said flanged portions being formed with engaging portions separated by spaced portions, and connecting means joining said downwardly extending portions at the engaging portions thereof.

19. A car truck side frame comprising spaced sheet-metal walls, the lower edges of which are flanged inwardly, downturned extensions on said flanged portions and provided with isolated abutting sections, connecting means at said sections, said connected flanged portions being spaced between connected sections, a journal box mounted at each end of the frame and provided with a lug formed with a bossed aperture therein, said apertured portion being positioned between said flanges and riveted thereto.

In testimony whereof I affix my signature.

CYRUS HANKINS.
